UNITED STATES PATENT OFFICE.

ROSWELL C. BAIRD, OF CUMBERLAND, WISCONSIN.

DESIGN FOR A BADGE, EMBLEM, OR SIMILAR ARTICLE.

43,100.

Specification for Design.

Patented Oct. 8, 1912.

Application filed July 12, 1912. Serial No. 709,072. Term of patent 7 years.

To all whom it may concern:

Be it known that I, ROSWELL C. BAIRD, a citizen of the United States, residing at Cumberland, in the county of Barron and the State of Wisconsin, have invented a new, original, and ornamental Design for a Badge, Emblem, or Similar Article, of which the following is a specification, reference being had to the accompanying drawing, forming part thereof.

The figure is a plain view of an ornamental pin showing my new design.

I claim—

The ornamental design for a badge, emblem or similar article, as shown.

ROSWELL C. BAIRD.

Witnesses:

FERN WRIGHT,
HELEN M. WRIGHT.
